UNITED STATES PATENT OFFICE

OTTO W. EISEN, OF HOLLIS, NEW YORK, ASSIGNOR TO PETER J. COSTIGAN, OF WATERBURY, CONNECTICUT

APPARATUS FOR REDUCING STIFFNESS FROM SHOES

Application filed January 13, 1930. Serial No. 420,334.

This invention relates to improvements in apparatus to ease shoes to reduce therefrom the stiffness inherent therein when new.

An object of the invention is to provide an improved apparatus of simple and practical construction by means of which a shoe may have imparted thereto movements simulating those occasioned when the shoe is used for walking.

Another object is to produce distinct oscillatory movements in different parts of a shoe about axes extending transverse to each other.

A further object is to affix the sole of a shoe to a rocker member which will impart to said sole a torsional action relative to the heel of said shoe, and to mount said heel upon a vertically oscillating platform the movements of which will cause the vamp and sole of the shoe to bend in a manner similar to that effected when being used for walking.

The above and other objects will appear more clearly from the following detailed description, when taken in connection with the accompanying drawings, which illustrate a preferred embodiment of the inventive idea.

In the drawings—

Figure 1 is a side elevation of the apparatus, partly broken away and shown in section;

Figure 2 is a fragmentary top plan view thereof, partly broken away;

Figure 3 is a vertical transverse section; and

Figure 4 is a section on the line 4—4 of Figure 1.

The apparatus is shown as comprising a base 5 having extending upwardly therefrom along its longitudinal center the aligned bearings 6 and 7 in which is supported a rocker member 8 adapted for oscillation in the bearings and provided at its rear end with a crank arm 9. Mounted upon the rocker member 8 and adjustable longitudinally thereon is a sole-clamping device which comprises a bearing block 10 having an aperture therein for receiving the rocker member and a set screw 11 for engaging the latter to secure the block in adjusted positions. Carried by the block 10 and extending on opposite sides

thereof is the sole-supporting plate 12 having slots 13 therein in which are slidably mounted the clamps 14 for engaging opposite edges of the sole of the shoe 15, as shown in Figure 1. These clamps 14 are adjusted by means of the rod 15 having opposite threads at its ends engageable with the depending portions 16 of the clamps 14 so that, when the rod 15 is turned by means of a key engaged with the square portion 17 at either end of said rod 15 and the latter turned, the clamps 14 may be adjusted toward and away from each other.

On opposite sides of the rocker member 8 and also extending upwardly from the base 5 are the bearings 18 in which a platform 19 is pivotally supported for vertical movement about an axis which extends transverse to the axis of the rocker member 8 and to the longitudinal axis of the shoe 15. This platform 19 is adapted to support the heel of the shoe 15 and for this purpose the platform, at its rear end, is provided with a standard 20. Slidable vertically on this standard is a sleeve 21 having ring members 22 and 23 at its upper and lower ends adapted to receive a leg form 24 to the lower end of which is detachably secured a shoe form 25 insertable into the shoe 15 prior to the latter being lowered into position upon the platform 19 and engaged by the clamps 14. To secure the shoe in this position the sleeve 21 is provided with parallel longitudinal slots 26 forming a flexible section 27 therein adapted to be engaged by the eccentric portion 28 of a clamping handle 29 which, when forced down to the position shown in Figure 1, will frictionally retain the sleeve 21 in an adjusted position on the standard 20. With the shoe thus adjusted upon the apparatus a vertical oscillation of the platform 19 will impart to the shoe, the sole of which is now held by the clamps 14, a movement simulating that produced when the shoe is used for walking wherein the vamp of the shoe will be flexed. At the same time that the platform is moved about its pivot the rocker member 8 is also oscillated through the medium of the crank arm 9 and this movement will impart to the sole of the shoe a torsional action rela-

tive to the heel which will also have the effect of reducing stiffness in the shoe.

To effect the oscillations of the rocker member 8 and platform 19 there is preferably utilized a common source of power which, as shown, consists of an electric motor 30 mounted upon the base 5 and the shaft of which has a worm 31 thereon for engaging the gear 32 of a rotatable element 33 also supported upon said base. This element is provided therein with a cam groove 34 in which is engaged a roller 35 carried by the free end of the crank arm 9 so as to impart oscillations to said arm as the element 33 is driven by the motor 30. The pivotal movements of the platform 19 are accomplished by connecting the same to the rotatable element 33 by means of the pitman rod 36. Thus, the apparatus simultaneously effects movements of the heel 20 of the shoe relative to the sole about an axis transverse to the vamp of the shoe, and also a torsional action of the sole relative to the heel.

What is claimed is:

- 25 1. In an apparatus for reducing stiffness from shoes, supporting elements for the sole and heel of a shoe, and means to operate said elements to impart movements to portions of said shoe about axes extending transversely of each other.
2. In an apparatus for reducing stiffness from shoes, supporting elements for the sole and heel of a shoe, and means to operate one of said elements to impart to said sole a torsional movement relative to said heel.
3. In an apparatus for reducing stiffness from shoes, means to hold the sole of a shoe, a platform supporting the heel of the shoe movable about an axis extending transversely of the shoe, and means to oscillate said platform.
4. In an apparatus for reducing stiffness from shoes, a rocker member, a sole clamp carried thereby for supporting a shoe longitudinally of said rocker member, and means to rock said member to torsion said sole.
5. In an apparatus for reducing stiffness from shoes, means to hold the sole of a shoe, a platform supporting the heel of the shoe movable about an axis extending transversely of the shoe, a rocker member extending longitudinally of said shoe and carrying said sole-holding means, and means to rock said member and oscillate said platform.
- 55 6. In an apparatus for reducing stiffness from shoes, means to hold the sole of a shoe, a platform supporting the heel of the shoe movable about an axis extending transversely of the shoe, a rocker member extending longitudinally of said shoe and carrying said sole-holding means, a crank for said rocking member, a pitman connected to said platform, and a rotary element to which said crank and pitman are operatively joined.
7. In an apparatus for reducing stiffness

from shoes, a base, standards thereon, a rocker member supported in certain of said standards, a platform pivoted to the other standards and adapted to support the heel of a shoe, means to secure the sole of said shoe to said rocker member, means carried by the platform for supporting said heel thereon, and a driven element mounted on said base and common to said rocker member and platform for oscillating the same.

8. In an apparatus for reducing stiffness from shoes, a base, standards thereon, a rocker member supported in certain of said standards, a platform pivoted to the other standards and adapted to support the heel of a shoe, means to secure the sole of said shoe to said rocker member, means carried by the platform for supporting said heel thereon, a driven element mounted on said base and common to said rocker member and platform for oscillating the same, and a motor also on said base for operating said driven element.

In testimony whereof I have affixed my signature.
